DESIGN FOR A PORTABLE BASKETBALL GOAL

Gerald A. Gibson, Excelsior, Minn.

Application August 7, 1944, Serial No. 114,756

Term of patent 14 years

(Cl. D34—5)

To the Commissioner of Patents:

Be it known that I, Gerald A. Gibson, a citizen of the United States and residing in the city of Excelsior, county of Hennepin, and State of Minnesota, have invented a new, original, and ornamental Design for Portable Basketball Goal, of which the following is a specification, reference being had to the accompanying drawings, forming a part thereof, wherein—

Fig. 1 is a perspective view of a portable basketball goal showing my new design;

Fig. 2 is a front elevational view thereof.

Fig. 3 is a side view thereof, and

Fig. 4 is a plan view.

I claim:

The ornamental design for a portable basketball goal, as shown.

GERALD A. GIBSON.
